UNITED STATES PATENT OFFICE.

ARMIN ELMENDORF, OF CHICAGO, ILLINOIS.

METHOD OF AND APPARATUS FOR DRYING WOOD VENEER.

Application filed December 20, 1922. Serial No. 607,927.

To all whom it may concern:

Be it known that I, ARMIN ELMENDORF, a citizen of the United States, residing at Chicago, county of Cook, State of Illinois, have invented a certain new and useful Improvement in Methods of and Apparatus for Drying Wood Veneer, and declare the following to be a full, clear, and exact description of the same, such as will enable others skilled in the art to which it pertains to make and use the same, reference being had to the accompanying drawings, which form a part of this specification.

The common method of handling wood veneer is to cut or tear it into sheets as it is formed from the log, the sheets being then dried and reaching the consumer in what should be a flat dry state. There are several common methods of drying, namely, between hot plates, between rolls in a heated chamber, and in kilns. It is very seldom that a sheet of veneer emerges from the ordinary drying process without being warped and cracked. Therefore, although the ordinary drying methods are comparatively slow and costly, they do not result in the production of uniformly flat, sound sheets, even though the sheets at the beginning of the drying processes may have been flawless.

When veneer is cut from the log it is in a wet state, that is, a state in which the moisture content is above what is known as the fiber saturation point. As long as the moisture content remains above the saturation point there is substantially no expansion or contraction of the veneer as the amount of moisture increases or decreases.

As soon as the moisture content drops below the saturation point, in the drying of the veneer, contraction across the grain begins. Consequently, when veneer is dried below the saturation point by passing it through a series of rolls, special provision must be made to compensate for the contraction of the veneer in order to prevent tearing the sheet or strip in two. Furthermore, since wood veneer possesses only a small degree of tensile strength across the grain, which is in the direction of the length of the strip or sheet as it is cut from the log, provision must be made to feed the veneer through the drying rolls in such a way that there be little or no tension resulting from the feeding means, quite apart from the tension which might be set up

due to the shrinking or contracting of the material.

The object of the present invention is to produce a simple and novel process for effectually and economically drying wood veneer, the drying taking place while the veneer is being unwound from one roll and wound up on another, without danger of tearing the veneer and in such a manner that the dried product will be flat and unwarped.

A further object of the present invention is to produce a simple and novel machine or apparatus for carrying out my improved method.

The various features of novelty whereby my invention is characterized will hereinafter be pointed out with particularity in the claims; but for a full understanding of my invention and of its objects and advantages reference may be had to the following detailed description taken in connection with the accompanying drawings, wherein:

Figure 1 is a longitudinal vertical section through a preferred form of apparatus for carrying out my invention;

Fig. 2 is a section taken approximately on line 2—2 of Fig. 1;

Fig. 3 is a view similar to Fig. 1, showing only a fragment of the machine, with one of the elements adjusted to a different position from that which it occupies in Fig. 1;

Fig. 4 is a view similar to Fig. 1, showing a modified form of apparatus; and

Fig. 5 is a section taken approximately on line 5—5 of Fig. 4.

Referring to Figs. 1 to 3, inclusive, 1, 2, 3 and 4 represent parallel horizontal rolls. The number of rolls will of course depend upon the nature of the work to be done and upon whether or not the drying operation is to be completed by a single passage of the veneer through the machine, or by passing the veneer through the machine more than once. However, since the principle of my invention does not depend upon these details I shall, for the sake of brevity, confine the detailed description to the specific machines illustrated. Adjacent to each roll is a concave steam chest 5 extending throughout the length thereof, each roll lying in the trough of the corresponding chest. The chests associated with the first and third rolls are arranged below the rolls, while the other two chests are arranged above the

rolls with which they co-operate. At opposite ends of the group of rolls just described are feed rolls 6 and 7 lying parallel with the other rolls and of the same diameter as the latter. The rolls are all driven at the same speed, but each roll is rotated in the opposite direction from the direction of rotation of the adjacent roll or rolls. This may be done in any suitable manner, as, for example, by means of a sprocket chain drive 8. Above the rolls 6 and 7 are shafts or drums 9 and 10, respectively, mounted for rotation and bodily vertical movements in suitable stationary guides 11 and 12 fixed to the frame 13 of the machine. A strip or long sheet of veneer A wound up on the shaft or roll 9, in a wet state, is placed in the machine so as to rest upon the feed roll 6, the veneer being wound up on the drum 20 or shaft in such a direction that when the machine is set in operation the roll of wet veneer will be frictionally driven by the feed roll 6 in a direction to unwind the veneer and feed it to the roll 1. The first 25 steam chest has a flange 14 extending approximately tangentially to both roll 1 and roll 6 across the gap between these two rolls; the free end of the veneer at the beginning of the operation dropping down on this 30 flange or shelf and being guided thereby into the trough of the steam chest and underneath roll 1. The rolls 1, 2; 3 and 4 are preferably covered with a blanket 15 or other absorbent material which will take 35 up the moisture driven out of the veneer by the heat of the steam chest and, after being carried clear of the veneer, permit the moisture to be driven off again. Between the first steam chest and the roll 2 is arranged 40 a guide 16, along which the veneer travels so as to be introduced between the upper half of the roll 2 and the stem chest overlying the latter. The guide, together with the adjacent portion of the first steam chest, 45 preferably forms a more or less sinuous surface, so that the distance along the same from the first drying roll to the second is greater than it would be if a flat shelf or platform were employed. Above the guide 50 16 is a co-operating guide 17, having a sinuous working face extending between the first heating roll and the second steam chest. Between the rolls 2 and 3 are lower and upper guides 18 and 19 similar to guides 16 55 and 17, but oppositely disposed so as to feed the work down from the top of the second roll to the under side of the third roll. Between the third and the fourth drying rolls are lower and upper guides 20 and 21, identical with the guides 16 and 17. Between the last drying roll and the feed roll 7 is an inclined guide 22 extending from near the top of the drying roll downwardly underneath the roll 7 and upwardly past 60 the opposite side of that roll so as to cause

the free end of the veneer, after passing the drying rolls, to travel underneath the roll 7 and then to the upper side thereof, where it may be wound up on the receiving shaft or drum 10. After the free end of the veneer has been attached to the receiving end or shaft, the latter will be frictionally driven from the feed roll 7 in a direction to cause the veneer to be wound up as it reaches the discharge end of the machine, the shaft or drum rising in the guides 12 as the number of layers of veneer thereon increases. 70

The guides 16 to 22, inclusive, need not extend continuously throughout the lengths of the rolls, but may be made in sections so as to form, in effect, a series of parallel separated tracks or channels between each pair of rolls; thus exposing both sides of the veneer to atmosphere in the spaces between consecutive rolls and permitting steam to 85 escape therefrom directly into the air. 90

When a full roll of veneer is placed into the right hand end of the machine, as viewed in Fig. 1, so as to rest on the feed roll 6, and the machine is set in operation, the veneer will be unwound without the exertion of any pull thereon and will be fed down underneath the first heating roll, which presses it against the steam chest and, through frictional engagement with the 95 veneer, feeds it along at the same speed as that at which it is delivered from the roll 6. As the free end of the veneer emerges from beneath the first heating roll, it enters between the sinuous guides 16 and 17, and is pushed ahead until it reaches the second heating roll, which in turn acts as a feeding means. In this way the veneer is pushed ahead and driven along through frictional engagement with the heating rolls until it reaches the discharge end of the machine, 100 where it will be wound up, as heretofore explained. The veneer does not fit closely in the space between the sinuous guides of each set, but these guides are spaced far enough apart so as to permit considerable freedom of movement of the veneer. In other words, an appreciable amount of slack is formed in the veneer between each two consecutive heating rolls and, if there should be such 110 shrinking of the veneer as would place the veneer under sufficient tension, if the veneer extended tangentially between the rolls, to cause the veneer to be torn, the creation of such a tension and the tearing of the veneer will be prevented by the possibility of simply taking up slack in the veneer between the rolls. If desired, the guides may be so constructed that they may be opened so as to permit all of the slack to be taken out of the veneer and permit it, if necessary, to straighten out completely between consecutive rolls. In the arrangement shown, the upper guide members 17, 19 and 21, are supported upon eccentrics 25, which may be 115 120 125 130

turned so as to raise these guides from positions indicated in Fig. 1 to a position corresponding to that shown in Fig. 3, in which latter figure the veneer is shown as extending in a flat condition between two of the rolls.

It will be seen that the veneer is bent alternately in opposite directions, such that the fibres in the veneer are caused to remain straight or, if warping has occurred, are first straightened and then caused to remain straight, whereby the veneer will leave the machine in a true flat condition. It will also be seen that the heat is applied first to one side of the veneer, and then to the other, thus avoiding the danger of case-hardening only one side and, at the same time securing a more efficient application of the heat than is possible where the transfer of the heat to the veneer must take place on only one face thereof.

In Figs. 4 and 5 I have illustrated a modified form of machine in which the heat is applied in the form of hot or warm air while the veneer is being fed along and being bent alternately in opposite directions. Referring to these figures, 31 and 32 represent two co-operating feed rolls, of which there may be any desired number of pairs; six such pairs being shown, suitably distributed along a supporting frame 33. The lower rolls are provided with a series of circumferential grooves 34 distributed lengthwise thereof. A series of long strips or thin bars 35 of spring steel or other suitable springy material extends lengthwise through the group of feed rolls, each bar lying in one of the grooves of each of the lower feed rolls. The bars are fastened at one end, as indicated at 36, to the frame of the machine, while the other ends of the bars are free. Between the upper rolls are placed suitable guides 37 conveniently made in the form of bars long enough to extend from one set of rolls to the next, lying directly above the strips or bars 35, and curved upwardly between the ends. Located midway between each pair of feed rolls is a roller 38 underlying the strips or bars 35 and having its axis parallel with the axes of the feed rolls. The rollers 38 are supported on the upper ends of standards 39 extending through and screw-threaded into suitable stationary pedestals 40. On the lower end of each standard is a worm wheel 41, meshing with a suitable worm 42 on a longitudinal shaft 43. There are preferably two sets of supporting standards, one at each end of the rollers, and therefore two worm shafts. Either worm shaft may be rotated in any suitable manner, the other being caused to rotate by means of a belt or chain 44 passing over suitable wheels or pulleys 45 fixed to the two worm shafts. The parts are so propor-

tioned that when the rollers are raised they bend the strips 35 in the upward direction, so that these strips, with the overlying guides 37, form curved passages through which the veneer must travel from one set of rolls to the next. When it is desired to enlarge these passages, the rollers are simply lowered, permitting the bars 35 to straighten, and thereby permitting the veneer to extend straight across from one set of rolls to the next, if desired.

The veneer to be dried is wound on a drum or shaft 9, as in the other form of machine, the roll of veneer being allowed to rest on the upper feed roll of the first set and moving down by gravity in the guiding bearings 11 as the veneer is unwound and the diameter of the roll decreases. At the other end of the machine the veneer is wound up on a shaft or drum 10, as in the other machine.

The feed rolls and the guides are enclosed in a housing 46 containing steam pipes 47 and suitable fans 48 for blowing the hot air across the veneer as it is traveling through the machine.

Either or both rolls of each set of rolls may be driven. In the arrangement shown, the upper rolls, alone, are adapted to be driven by means of a sprocket chain drive 49 connecting all of the rolls together and adapted to rotate the upper rolls in the same direction and at the same speed.

It will be noted that the rolls in either machine may first be driven in one direction and then in the other, causing the veneer to be passed through the machine first in one direction and then in the other, without removing it. This makes it possible to use a machine much smaller than would be necessary to dry the veneer during a single passage therethrough, since the veneer need only be run back and forth through the machine a sufficient number of times to dry it.

While I have illustrated and described in detail two satisfactory forms of machine, the first form adapted particularly for drying thin veneer and the second form adapted particularly for drying heavy veneer, by which my improved method may be carried out, I do not desire to be limited to such details, but intend to cover all forms, arrangements and series of steps which come within the definitions of my invention constituting the appended claims.

I claim:

1. The method of drying veneer which consists in passing it through successive feeding devices adapted to feed the veneer at a uniform speed, applying heat to the veneer during its passage, and causing the forming of slack in the veneer between consecutive feeding devices.

2. The method of drying veneer which consists in laying on the first roll of a series of feed rolls driven at the same speed a roll

of veneer wound in such direction that the veneer will be unwound by the frictional action of the said first feed roll and be advanced toward the second feed roll, causing the veneer to take a curved form between adjacent feed rolls, and applying heat during the passage of the veneer.

3. The method of drying veneer which consists in passing it through successive feeding devices adapted to feed it at a uniform speed, applying heat to the veneer during its passage, controlling the advancing veneer to cause it to take a curved shape between consecutive feeding devices, and thereafter permitting the curved portions to flatten out more or less as shrinking occurs.

4. The method of drying veneer which consists in passing it through successive feeding devices adapted to feed it at a uniform speed, applying heat to the veneer during its passage, causing the veneer to pass between curved guides in the spaces between

consecutive feeding devices, and spreading said guides apart as shrinkage occurs in order to provide slack to compensate for such shrinkage. 25

5. The method of drying wood veneer which consists in bending it alternately in opposite directions parallel with the fibres so as to keep the fibres straight and applying heat first to one side thereof and then to the other side. 30

6. A machine comprising a series of horizontal rolls rotatable at the same speed, each roll being rotatable in the opposite direction 35 from the immediately adjacent roll or rolls, steam chests co-operating with and having curved surfaces lying near said rolls, some of the chests being above certain of the rolls and the other chests being below the other 40 rolls.

In testimony whereof I sign this specification.

ARMIN ELMENDORF.
